UNITED STATES PATENT OFFICE.

PAUL GREINDL, OF BRUSSELS, BELGIUM.

MOVABLE INDEX-CARDS.

1,108,574.

Specification of Letters Patent. Patented Aug. 25, 1914.

Application filed April 16, 1914. Serial No. 832,220.

To all whom it may concern:

Be it known that I, PAUL GREINDL, baron, a subject of the King of the Belgians, and residing at Brussels, Belgium, have invented 5 certain new and useful Improvements in Movable Index-Cards, of which the following is a specification.

The methods of classing by means of movable index-cards are so practically advantageous, that nearly all the public and private 10 administrations adopted the same a long time since. However if an index-card is wrongly placed, no means are provided for detecting the same.

15 The object of my present invention is to provide a system of movable index-cards, enabling the cards which are not placed alphabetically to be detected instantly.

20 The invention is illustrated by way of example in the accompanying drawings, wherein—

Figure 1 shows an index-card provided with two alphabets, Fig. 2 shows an index-card provided with three alphabets, Fig. 3 25 is a general view of a number of index-cards arranged as in practical use.

The invention consists in providing index-cards of a particular form according to the first characters of which the principal words 30 of the cards are composed. This result may be attained by dividing one or more sides of each index-card in two equal parts (in the example illustrated in the accompanying drawings, the upper end of each index-card 35 is divided into two equal parts) and marking the alphabet on one or more lines. The characters A of both alphabets are placed in the central part of the index-card and on the lower line, if the alphabets are arranged on several horizontal lines. The characters of the alphabet are placed into rectangles. If an index-card is to be prepared, all the characters of the left hand portion will be cut away by means of scis- 40 sors as far as but not including the character corresponding to that with which the title of the card index commences. In the right hand portion all the characters as far as the

second character of the title will be similarly cut away. Should the index-card indicate 50 the word "Berlin" for instance, all the characters on the left as far as the character B will be cut away, and on the right all the characters as far as the character E will be similarly cut away. 55

In Figs. 1 and 2 the lines formed of dots and dashes indicate the manner of cutting the card for the word "Berlin." Now if the index-card prepared in this way is wrongly placed, say before the index-card indicating 60 "Bâle," the character E of the right hand side will project from the upper ends of the index-cards and instantly show the error.

If there is a great number of index-cards, 65 it may be advantageous to add one, two or more alphabets, either on the same side of the index-card or on a different side, these alphabets being marked on different horizontal lines. The index-cards will then be 70 similarly arranged with respect to the first three, four, etc., characters of the titles. The same method may of course be applied to numerals or any other signs.

Having fully described my invention, 75 what I claim and desire to secure by Letters Patent is:—

1. An improved index-card, comprising a substantially rectangular card, the characters of two alphabets marked in opposite 80 directions near the upper end of the card and intended to be cut away substantially as set forth.

2. An improved index-card, comprising a substantially rectangular card, the characters of several alphabets marked on different horizontal lines near one end of the card and intended to be cut away substantially as set forth.

In testimony whereof I affix my signature 90 in presence of two witnesses.

PAUL GREINDL.
